UNITED STATES PATENT OFFICE

JAMES R. HUGHES, OF SOUTH BEND, INDIANA, ASSIGNOR TO THE PIERCE-ARROW
MOTOR CAR COMPANY, OF BUFFALO, NEW YORK, A CORPORATION OF NEW YORK

DESIGN FOR A COMBINED FENDER, HEAD LAMP CASING, AND COMBINED PARKING
LAMP AND HORN CASING

Application filed October 29, 1932. Serial No. 45,641. Term of patent 14 years.

To all whom it may concern:

Be it known that I, JAMES R. HUGHES, a citizen of the United States of America, and resident of South Bend, in the county of St. Joseph and State of Indiana, have invented a new, original, and ornamental Design for a Combined Fender, Headlamp Casing, and Combined Parking Lamp and Horn Casing, of which the following is a specification, reference being made to the accompanying drawing, forming a part thereof.

In the drawing, Figure 1 is a perspective view of the combined fender, headlamp cas-

ing, and combined parking lamp and horn casing showing my new design, and Fig. 2 is a perspective view showing the design from a different angle than that illustrated in Fig. 1.

I claim:

The ornamental design for a combined fender, headlamp casing, and combined parking lamp and horn casing substantially as shown.

Signed by me at South Bend, Indiana, this 26 day of October, 1932.

JAMES R. HUGHES.
